(57) **CLAIM**

We claim the ornamental design for a basket for refrigerator, as shown and described.

DESCRIPTION

FIG. 1 is a perspective view of a basket for refrigerator showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view with the horizontal bar thereof being upright;

FIG. 9 is a front elevation view with the horizontal bar thereof being upright;

FIG. 10 is a right-side elevation view with the horizontal bar thereof being upright;

FIG. 11 is a top plan view with the horizontal bar thereof being upright;

FIG. 12 is a perspective view with the horizontal bar thereof being fallen-down;

FIG. 13 is a front elevation view with the horizontal bar thereof being fallen-down;

FIG. 14 is a right-side elevation view with the horizontal bar thereof being fallen-down; and,

FIG. 15 is a top plan view with the horizontal bar thereof being fallen-down.
